UNITED STATES PATENT OFFICE.

EDWIN D. GREENE, OF NEW YORK, N. Y., ASSIGNOR TO ARKELL SAFETY BAG COMPANY, OF NEW YORK, N. Y., A CORPORATION OF NEW YORK.

MACHINE FOR MAKING STRETCHABLE CRINKLED PAPER.

1,348,638.

Specification of Letters Patent.

Patented Aug. 3, 1920.

Application filed June 13, 1919. Serial No. 303,835.

To all whom it may concern:

- Be it known that I, EDWIN D. GREENE, a citizen of the United States, residing in the borough of Manhattan, city, county, and 5 State of New York, have invented certain new and useful Improvements in Machines for Making Stretchable Crinkled Paper, of which the following is a full, clear, and exact description.
- 10 This invention relates to a machine for making stretchable crinkled paper of the type that is used for packing and wrapping purposes.
- In the manufacture of crinkled paper it is 15 desirable that the paper be moistened before it is placed on the receiving roll and acted upon by the doctor to form the crinkles in the paper. After the paper has received these crinkles, it must again be dried and in 20 such a manner that the crinkles are not destroyed during the drying. The drying process requires a considerable amount of heat and renders the rooms more or less uncomfortable.
- 25 It is an object of this invention to condition the paper while in the web for being placed upon the receiving roll so that it may be crinkled by the doctor with a minimum amount of moisture content. By so 30 reducing the moisture content less heating will be required to subsequently dry the crinkled paper.
- Other objects of the invention will appear as the description proceeds.
- 35 In the drawings, wherein is shown a preferable embodiment of my invention, Figure 1 is an elevational view showing the general arrangement of parts;
- Fig. 2 is a top plan view, and
- 40 Fig. 3 is a sectional view on the line 3—3 of Fig. 1.
- In the drawings, wherein similar reference characters refer to similar parts throughout the several views, 4 represents 45 the main frame of the crinkling machine. At one end of this frame on a suitable bracket 5, the supply roll 6 of paper is carried.
- A closed steam chest 7 is carried by the 50 frame. This chest has a pair of doors 8 which may be opened to obtain access into the interior thereof. The upper regions of the steam chest have two slotted openings 9 and 10 through which the paper may be 55 passed. Within the chest is a suitable set of guiding rolls 11, which direct the paper
- in a tortuous path through the chamber. It is desirable that the openings 9 and 10 permit the free passage of the paper, and in order to seal these openings the web 6' is 60 caused to pass between the co-operating pairs of rolls 12 and 13 which are carried by suitable framework 14 and 15. The frames 14 and 15 have rectangular openings to accommodate the rolls 12 and 13. The upper roll 65 rests upon the paper and therefore will not permit the steam to pass outwardly from the chest. The moistened paper is drawn through the steam chest and about the rolls 11 through the rolls 13 and the slit 10 by 70 means of a set of squeeze rolls 16 which may be adjusted by hand wheels 16', whereby the moisture on the web of paper is squeezed through its fibers, permeating and softening the same. These rolls feed the web on 75 toward the receiving roll. The lower of these rolls is driven by belt 17 carried on the power shaft 18 which is supported on the main frame 4. The shaft 18 also carries a smooth metal receiving roll 19. 80
- After the web 6' has passed between the rolls 16, it is fed about a pressure-applying roll 20 which squeezes the wetted web of paper against the receiving roll, expelling any 85 excess moisture which may remain in the paper and pressing the wet paper in close adherence to the receiving roll. 21 represents the doctor which is held by suitable mechanism and acts to form the crinkles in the paper. 90
- The amount of steam which is admitted to the box may be readily controlled by valves, not shown, in the supply line 22, and the condensed water drained away through pipe 23. Opening the doors 8 permits access to the chest and so that the web of paper from the roll 6 may be started in the tortuous path about the rolls 11 in the chamber. While passing through the chamber, the paper will absorb moisture from the steam, and thereby become softened without being 100 soaked in water. It will, therefore, not require so much heating to dry the paper after it has been crinkled by the doctor. 105
- If desired, one or more additional pairs of squeeze rolls 24 through which the paper passes may be located within the steam chest, such rolls being provided with adjusting hand wheels 24' and being driven by a belt 25 which passes around a pulley 26 on the lower roll 16 at the farther end and around a pulley 27 at the farther end of the lower 110

roll 24. Of course, as many pairs of squeeze rolls or other squeezing devices may be employed as circumstances require.

While I have shown my invention in what I believe to be the most efficient and desirable form, it will be understood that various changes may be made without departing from the scope of the invention.

I claim:

- 10 1. In a machine for making stretchable crinkled paper, the combination with a smooth faced receiving roll adapted to have paper deposited thereon and a doctor associated with the roll against which the paper is carried for crinkling, of a steam chest in advance of the receiving roll through which the paper passes for moistening, and means for squeezing into the paper the moisture deposited thereon by the steam.
- 20 2. In a machine for making stretchable crinkled paper, the combination with a smooth faced receiving roll adapted to have paper deposited thereon and a doctor associated with the roll against which the paper is carried for crinkling, of a steam chest in advance of the receiving roll through which the paper passes for moistening, and rolls for squeezing into the paper the moisture deposited thereon by the steam.
- 30 3. In a machine for making stretchable crinkled paper, the combination with a smooth faced receiving roll adapted to have paper deposited thereon and a doctor associated with the roll against which the paper is carried for crinkling, of a steam chest in advance of the receiving roll through which the paper passes for moistening, and adjustable rolls for squeezing into the paper the moisture deposited thereon by the steam.
- 40 4. In a machine for making stretchable crinkled paper, the combination with a smooth faced receiving roll adapted to have paper deposited thereon and a doctor associated with the roll against which the paper is carried for crinkling, of a steam chest in advance of the receiving roll through which the paper passes for moistening, and rolls driven from the receiving roll for squeezing into the paper the moisture deposited thereon by the steam.
- 50 5. In a machine for making stretchable crinkled paper, the combination with a smooth faced receiving roll adapted to have paper deposited thereon and a doctor associated with the roll against which the paper is carried for crinkling, of a steam chest in advance of the receiving roll through which the paper passes for moistening, means for squeezing into the paper the moisture deposited thereon by the steam, and means for pressing the paper closely against the receiving roll.
- 60 6. In a machine for making stretchable crinkled paper, the combination with a smooth faced receiving roll adapted to have
- 70 paper deposited thereon and a doctor associated with the roll against which the paper is carried for crinkling, of a steam chest having openings therein for admitting and delivering the paper, and means for squeezing into the paper the moisture deposited thereon by the steam.
- 75 7. In a machine for making stretchable crinkled paper, the combination with a smooth faced receiving roll adapted to have paper deposited thereon and a doctor associated with the roll against which the paper is carried for crinkling, of a steam chest having openings therein for admitting and delivering the paper, and rolls for squeezing into the paper the moisture deposited thereon by the steam.
- 80 8. In a machine for making stretchable crinkled paper, the combination with a smooth faced receiving roll adapted to have paper deposited thereon and a doctor associated with the roll against which the paper is carried for crinkling, of a steam chest having openings therein for admitting and delivering the paper, and adjustable rolls for squeezing into the paper the moisture deposited thereon by the steam.
- 85 9. In a machine for making stretchable crinkled paper, the combination with a smooth faced receiving roll adapted to have paper deposited thereon and a doctor associated with the roll against which the paper is carried for crinkling, of a steam chest having openings therein for admitting and delivering the paper, means for squeezing into the paper the moisture deposited thereon by the steam, and means for pressing the paper closely against the receiving roll.
- 90 10. In a machine for making stretchable crinkled paper, the combination with a smooth faced receiving roll adapted to have paper deposited thereon and a doctor associated with the roll against which the paper is carried for crinkling, of a steam chest having openings therein for admitting and delivering the paper, means for sealing the openings, and means for squeezing into the paper the moisture deposited thereon by the steam.
- 100 11. In a machine for making stretchable crinkled paper, the combination with a smooth faced receiving roll adapted to have paper deposited thereon and a doctor associated with the roll against which the paper is carried for crinkling, of a steam chest having openings therein for admitting and delivering the paper, means comprising superposed rolls adapted to receive the paper therebetween for sealing the openings, and means for squeezing into the paper the moisture deposited thereon by the steam.
- 110 12. In a machine for making stretchable crinkled paper, the combination with a smooth faced receiving roll adapted to have paper deposited thereon and a doctor associated with the roll against which the paper is carried for crinkling, of a steam chest having openings therein for admitting and delivering the paper, means comprising superposed rolls adapted to receive the paper therebetween for sealing the openings, and means for squeezing into the paper the moisture deposited thereon by the steam.
- 120 13. In a machine for making stretchable crinkled paper, the combination with a smooth faced receiving roll adapted to have paper deposited thereon and a doctor associated with the roll against which the paper is carried for crinkling, of a steam chest having openings therein for admitting and delivering the paper, means comprising superposed rolls adapted to receive the paper therebetween for sealing the openings, and means for squeezing into the paper the moisture deposited thereon by the steam.
- 130 14. In a machine for making stretchable crinkled paper, the combination with a smooth faced receiving roll adapted to have paper deposited thereon and a doctor associated with the roll against which the paper is carried for crinkling, of a steam chest having openings therein for admitting and delivering the paper, means comprising superposed rolls adapted to receive the paper therebetween for sealing the openings, and means for squeezing into the paper the moisture deposited thereon by the steam.

- ciated with the roll against which the paper is carried for crinkling, of a steam chest having openings therein for admitting and delivering the paper, means comprising 5 superposed free running rolls adapted to receive the paper therebetween for sealing the openings, and means for squeezing into the paper the moisture deposited thereon by the steam.
10. 13. In a machine for making stretchable crinkled paper, the combination with a smooth faced receiving roll adapted to have paper deposited thereon and a doctor associated with the roll against which the paper is carried for crinkling, of a steam chest, means to direct the paper through the chest in tortuous fashion, and rolls for feeding the paper from the steam chest toward the receiving roll.
15. 14. In a machine for making stretchable crinkled paper, the combination with a smooth faced receiving roll adapted to have paper deposited thereon and a doctor associated with the roll against which the paper is carried for crinkling, of a steam chest, means comprising suitably arranged rolls to direct the paper through the chest in tortuous fashion, and rolls for feeding the paper from the steam chest toward the receiving roll.
20. 15. In a machine for making stretchable crinkled paper, the combination with a smooth faced receiving roll adapted to have paper deposited thereon and a doctor associated with the roll against which the paper is carried for crinkling, of a steam chest, means for comprising suitably arranged
25. 30. 35. 40. 45. 50. 55. 60. 65. 70. rolls to direct the paper through the chest in tortuous fashion, means to obtain access to the directing rolls, and rolls for feeding the paper from the steam chest toward the receiving roll.
16. The method of conditioning paper for crinkling which comprises subjecting the paper to an atmosphere of steam to moisten the fibers and feeding the steamed paper on to a receiving roll.
17. The method of conditioning the paper for crinkling which comprises subjecting the paper to an atmosphere of steam to moisten the fibers, subjecting the steamed paper to the action of squeeze rolls and feeding the steamed paper on to a receiving roll.
18. In combination, a steam chest for pre-treating paper for crinkling, means for directing the paper through the chest, and squeeze rolls within the steam chest through which the paper is adapted to be passed.
19. In combination, a steam chest for pre-treating paper for crinkling, means for directing the paper through the chest, and adjustable squeeze rolls within the steam chest through which the paper is adapted to be passed.
20. In combination, a steam chest for pre-treating paper for crinkling, rolls for directing the paper through the chest in a tortuous fashion, and squeeze rolls intermediate the directing rolls through which the paper is adapted to be passed.

This specification signed this 6th day of June 1919.

EDWIN D. GREENE.
